CLAIM

The ornamental design for a fluid flow control component as shown and described.

DESCRIPTION

This invention was made with government support under Contract No. 2127461 awarded by The National Science Foundation. The government has certain rights in the invention.

FIG. 1 is a front perspective view of a first embodiment of a fluid flow control component;

FIG. 2 is a back perspective view of the component of FIG. 1;

FIG. 3 is a front view of the component of FIG. 1;

FIG. 4 is a back view of the component of FIG. 1;

FIG. 5 is a right side view of the component of FIG. 1;

FIG. 6 is a left side view of the component of FIG. 1;

FIG. 7 is a top view of the component of FIG. 1;

FIG. 8 is a bottom view of the component of FIG. 1;

FIG. 9 is a front perspective view of a second embodiment of a fluid flow control component;

FIG. 10 is a back perspective view of the component of FIG. 9;

FIG. 11 is a front view of the component of FIG. 9;

FIG. 12 is a back view of the component of FIG. 9;

FIG. 13 is a right side view of the component of FIG. 9;

FIG. 14 is a left side view of the component of FIG. 9;

FIG. 15 is a top view of the component of FIG. 9; and,

FIG. 16 is a bottom view of the component of FIG. 9.

The broken lines in the figures depict portions of the article which form no part of the claimed design.

The short-dash/long-dash broken lines illustrate boundary lines and form no part of the claimed design.

1 Claim, 14 Drawing Sheets
